(57) **CLAIM**

I claim the ornamental design for an infrared thermometer, as shown and described.

DESCRIPTION

FIG. 1 is a perspective view of an infrared thermometer according to an embodiment.

FIG. 2 is a front view of the infrared thermometer of FIG. 1.

FIG. 3 is a rear view of the infrared thermometer of FIG. 1. FIG. 4 is a left side view of the infrared thermometer of FIG. 1.

FIG. 5 is a right side view of the infrared thermometer of FIG. 1.

FIG. 6 is a top view of the infrared thermometer of FIG. 1; and,

FIG. 7 is a bottom view of the infrared thermometer of FIG. 1.

The broken line showing of the environment is for illustrative purposes only and forms no part of the claimed design.
